SUSPENDED ELECTRIC LAMP

Peter Hamburger, 36 Commerce St.,
New York, N.Y. 10014

Filed Jan. 21, 1970, Ser. No. 21,015

Term of patent 14 years

Int. Cl. D26—02

U.S. Cl. D48—23

FIG. 1 is a perspective view of the suspended electric lamp showing my new design;

FIG. 2 is a front elevational view thereof on a reduced scale;

FIG. 3 is a side elevational view thereof on a reduced scale; and

FIG. 4 is a plan view thereof on a reduced scale.

The support cord and ceiling are indicated in broken lines for illustrative purposes only.

I claim:

The ornamental design for a suspended electric lamp, substantially as shown and described.
